United States Patent Office

Des. 178,363
Patented July 31, 1956

178,363

PIPE CUTTER

Eugene P. Halligan, Chicago, Ill.

Application July 20, 1955, Serial No. 37,047

Term of patent 14 years

(Cl. D54—13)

FIG. 1

FIG. 2

FIG. 3

FIG. 5

FIG. 4

Fig. 1 is a side elevational view of a pipe cutter embodying my new design;

Fig. 2 is a top plan view thereof;

Fig. 3 is a bottom plan view thereof;

Fig. 4 is a front elevational view thereof, viewing Fig. 3 from the left; and

Fig. 5 is a rear elevational view thereof, viewing Fig. 3 from the right.

I claim:

The ornamental design for a pipe cutter, as shown.
